The ornamental design for a case for electronic device, substantially as shown and described.

DESCRIPTION

FIG. 1 is a perspective view of a case for electronic device. FIG. 2 is a rear view of the case for electronic device shown in FIG. 1.

FIG. 3 is a front view of the case for electronic device shown in FIG. 1.

FIG. 4 is a first side view of the case for electronic device shown in FIG. 1.

FIG. 5 is a second side view of the case for electronic device shown in FIG. 1.

FIG. 6 is a top view of the case for electronic device shown in FIG. 1.

FIG. 7 is a bottom view of the case for electronic device shown in FIG. 1; and,

FIG. 8 is a cross-sectional view of the case for electronic device shown in FIG. 1, taken in the direction of cut-line 8-8 in FIG. 2.

Portions of the case for electronic device shown in broken lines form no part of the claimed design.
